ODD-EVEN AIR VALVE SYSTEM

Bjarne Junge, Los Gatos, and Russell A. Stauffer, San Jose, Calif., assignors to International Business Machines Corporation, Armonk, N.Y., a corporation of New York

Filed Jan. 3, 1966, Ser. No. 518,418

6 Claims. (Cl. 243—1)

This invention relates to pneumatic conveying systems in general and more particularly to a pneumatic conveying system for use in transporting carriers to and from a large file of carriers stored in drawers which are selectively positioned relative to file pneumatic access channels.

Recently, several large scale information storage and retrieval systems have evolved. In one recently developed system, a number of information bearing chips are stored in individual cells. The cells are transported between their respective files and an I/O station through pneumatic conveying tubes. In the file itself, a number of cells are stored in rectangular matrix form in drawers. Each drawer includes both cell pockets for loosely supporting the cells and at least one column of empty cell pockets which are enlarged to provide access pockets which allow passage of cells through them. The drawers are stacked to make a file. When the drawers are at the home position, all of the access pockets are in alignment so that a column of access channels is provided up through the file. When a cell is to be accessed, its drawer is moved so that the cell is positioned in alignment with a file access channel and air is applied to cause it to move up through the file. Only the access channel with which the desired cell is aligned will have air applied to it. In larger files of this type, a number of columns of access channels is utilized to reduce the extent of drawer movement. A more detailed description of this type of file will be found in U.S. patent application Serial No. 423,015 entitled, "Air Flow Control and Cell Deflector Blade System with Direct Access Matrix File," filed January 4, 1965, assigned to the assignee of the subject invention.

To expand the storage capacity of an information storage and retrieval system of the type heretofore described, additional files are added rather than the adding of drawers to a single file. The adding of files, however, has been costly from the standpoint of systems throughput. The reason for this is that the same air supply which is used to lift a selected cell from the file, is also used to propel the cell down through the systems pneumatics which includes a common tube portion adjacent the I/O terminal. This arrangement results in, first, a lack of sufficient velocity through the common tube portion of the system. This lack of velocity is due to the loss of air in the file itself. This loss results from the relatively loose fit which exists between the drawers which must be provided to allow movement of the drawers relative to each other. Secondly, the file itself is necessarily tied up and cannot be repositioned until the cell has been received at its destination since the air supply, as heretofore stated, which propels the cell down through the systems pneumatics, originates below the file and passes up through the file, through the access channels which the cell passes through.

An object of the present invention is to provide a novel pneumatic air valve system for use in selective accessing.

Another object of the present invention is to provide a new pneumatic system for transporting carriers between a file, through a common tube portion and an I/O unit.

Another object of the present invention is to provide a new pneumatic system wherein the pneumatic source which lifts carriers from a file is replaced, after the carrier has entered the file pneumatic system effectively with an independent pneumatic source.

2

Another object of the present invention is to provide a new air valve system for selectively applying air to one of two file pneumatic tubes to cause a carrier to be transported from the carrying tube.

Other and further objects and advantages of the invention will be apparent from the following more particular description of the preferred embodiment of the invention as illustrated in the accompanying drawings in which:

FIG. 1 is an isometric view illustrative of the file pneumatic system of a prior art system which may be utilized in conjunction with the present invention;

FIG. 2 is a cutaway view of a pair of file I/O tubes, an air selector valve and an object selector valve;

FIG. 3 is a cutaway view of the air selector valve and object selector valve of FIG. 2 in reverse position to that of FIG. 2; and

FIG. 4 is an isometric view of a linkage and actuator which may be utilized to position the air selector valve and object selector valve of FIGS. 2 and 3.

Briefly, each file accessing channel is connected to a file pneumatic tube. The file pneumatic tubes are connected in pairs at one extremity. An air selector valve and an object selector valve are connected to the opposite extremity of each pair such that air may be applied to either tube. A cell is transported from an associated file which may be of the type wherein selected cells are pneumatically lifted from an associated file up into one of the two tubes in the pair through a file accessing deflector valve. After the cell has cleared the deflector valve, the deflector valve is shut and air is applied to the other file tube of the pair to propel the cell out through its file I/O tube through the object selector valve to the common pneumatic tube. If the cell had been received in the other tube of the pair, the object selector valve and air selector valve would have been reversed such that air would have been applied to cause the cell to move out of the other tube. To return a cell to the file, the above sequence is reversed.

For a more detailed description, refer first to FIG. 1. The particular type of file which is utilized is not important from the standpoint of the subject invention. As is obvious, the main criteria is that a cell must be delivered into one of the two tubes of the pair of file I/O tubes.

A cell can be delivered into one of the two tubes in various ways. However, the subject pneumatic valve system has been successfully utilized in conjunction with a file of the type as shown and described in the aforementioned patent application Serial No. 423,015. For purposes of clarity, there is shown in FIG. 1, a schematic of the three dimensional file of this patent application. In FIG. 1, the drawers of the file which are positioned to place cells in accessing relationship to the access channels are not shown for purposes of simplicity. In FIG.

1, three columns of accessing channels 2, 3 and 4 are provided in the file 1. These channels are, of course, formed by the through pockets of the drawers. As shown in FIG. 1, the drawers of the file must all be at the home position to provide the through channels up through the file. Additionally, the drawers would be six cell pockets in width since they are six pneumatic accessing channels in each of the accessing columns 2, 3 and 4. The drawers, as described in the patent application, may be positioned such that any cell can be brought into alignment with any of the access channels of the file 1. A pressurized air supply is selectively connectable to an air supply valve 5 such that pressurized air may be applied through the valve 5 into the channel 6. Air valve means are provided such that the air supply through valve 5 may be connected to any one of the file access channels. As further described in the aforementioned patent application, the file accessing channel to which air is applied

65

70

and with which a desired cell is in alignment has a cell and air deflector valve which is selectively operable to allow it to communicate with its file I/O tube. Thus, a given cell may be caused to move from its tray, up through the file access channels into the upper deck designated generally at 7 which consists of, as shown in FIG. 1, three sets of file I/O tubes 8, 9 and 10. Each set has two file I/O tubes which are connected by means of the air selector valves and object selector valves of FIGS. 2 and 3 to a file common I/O tube 11.

For a more detailed description of the pneumatic system and valve, refer next to FIG. 2. In FIG. 2 is shown two file tubes 20 and 21 which are connected at one extremity 22 to each other, and at the other extremity are connected to an air selector valve generally designated at 23, and an object selector valve generally designated at 24. The object selector valve 24 has its opposite extremity 25 connected to the file common I/O channel (not shown) while the air selector valve 23 has its opposite extremity connected to a source of air through tube 26. Intermediate their extremities, the file I/O tubes 20 and 21 are connected to at least one deflector valve generally designated at 27. A detailed description of this deflector valve 27 will not be included. The operation of the valve is such that when it is in the position as shown in FIG. 2, a cell 28 may be received from or returned to its associated file access channel while when it is closed, it pneumatically seals its associated file access channel from the file I/O tubes 20 and 21. A more detailed description of a valve similar to that of valve 27 will be found in a co-pending U.S. patent application assigned to the assignee of the subject invention entitled "Pneumatic Carrier Selector Valve, Decelerator and Hold Mechanism," Serial No. 388,377, filed August 10, 1964.

The air selector valve 23 contains an air deflector blade 29 which pivots around a pin, not shown, at point 30. In the position as shown in FIG. 2, the air from the tube 26 enters the chamber 31 of the air selector valve in the direction as shown by arrow 32, over the blade 29 through the channel member 33 and out of the window 34 into the upper file I/O tube 20. When blade 29 is positioned as shown in FIG. 2, the object selector blade 35 of the object selector valve 24 is at its uppermost position as shown in FIG. 2. The blade 35 has its extremity 36 against the stop 37 of the object selector valve such that a path is provided from the lower file I/O tube 21, through the object selector valve and out the file tube through opening 25.

The air blade 29 is caused to move into the position as shown in FIG. 2 by selective rotation of shaft 38 while the object selector blade 35 is caused to move into the position as shown in FIG. 2 by rotation of sleeve 39 affixed thereto. In operation, air is applied through tube 26 which passes through the housing 31 and is directed by means of the blade 29 and channel 33 through window 34 into the file I/O tube 20. The air then passes down through the tube 20 as shown by the arrow associated with tube 20, around the connecting end 22, into file I/O tube 21 only when valve 27 is closed. When a cell 28 has been positioned in the file I/O tube 21, the file deflector valve 27 is closed such that its associated file channel is sealed from the file I/O tube 21. When this occurs, the pneumatic pressure from file tube 20 then passes through file tube 21 conveying the cell out through the file tube 21, through the object selector valve 24 and out the opening 25 to the file common I/O channel.

In FIG. 3, the air selector valve 23 and object selector valve 24 are shown in the other extreme position from that of FIG. 2. Thus, as shown in FIG. 3, the air blade 29 has been rotated up so that the air from the tube 26 is directed through a lower window, not shown, into the lower file I/O tube 21 while the object selector blade 35 has been pivoted such that a cell from the upper file I/O tube 20 is directed down through the object selector

valve 24, through the opening 25 into the file common I/O tube or channel.

A butterfly valve 26A is shown in FIGS. 2 and 3 which is operable to block the pneumatic supply from the air selector valve 23. This butterfly valve is, when carriers are to be transported from the file tubes to the common file I/O channel, in the position as shown in FIGS. 2 and 3 such that the pneumatic supply is connected to the air selector valve 23. However, when a carrier is returned from the common file I/O channel, it is transported by means of its own pneumatic supply up through the object selector valve into the selected file tube, the pneumatic supply must be effectively disconnected from the air selector valve. Thus, butterfly valve 26A is operable during this return operation to effectively disconnect the pneumatic air supply from the air selector valve 23.

In FIG. 4 is shown a mechanism for selectively operating the object selector valve 24 and the air selector valve 23. A solenoid actuator 40 is provided with an actuator line 41 to which is applied electrical control signals. The shaft 42 of the solenoid 40 is pivotally connected by means of a pin 43 to linkages 44 and 45. Linkage 45 is pivotally connected by means of a pin 46 to arm 47 which is fixedly connected to the rod 38 which drives the air selector blade 29. Linkage 44 is pivotally connected around pin 48 to arm 49 which is fixedly connected to sleeve 39 which drives the object selector blade 35. The mechanism of FIG. 4 is shown in the position that it assumes when the blades are in the position of FIG. 2. When the rod 42 is caused to move to the right, the object selector blade and air selector blade are moved into the position as shown in FIG. 3.

For purposes of simplicity, the description of the subject pneumatic valving system has been, as in FIGS. 2 and 3, of a single pair of file tubes being served by the object selector valve and air selector valve combination. However, as will be obvious to those skilled in the art, in an actual system, undoubtedly more than a single pair of file tubes would be utilized. In the larger system, a single object selector valve and air selector valve could still be utilized. In the larger system, one tube of each pair of tubes would be connected by means of a manifold switch to what corresponds in FIGS. 2 and 3 to the tube 20 while the other tubes of the pairs would be connected by means of a second manifold switch to tube 21. The manifold switches then would be operative to connect the object selector valve-air selector valve to a selected pair of file tubes. A manifold switch which is ideally suited for this type of application is shown and described in U.S. patent application Serial No. 490,040 entitled "Pneumatic Carrier Accessing System," filed September 24, 1965, assigned to the assignee of the subject invention.

In summary, each file accessing channel is connected to a file pneumatic tube. The file pneumatic tubes are connected in pairs at one extremity. An air selector valve and an object selector valve are connected to the opposite extremity of each pair such that air may be applied to either tube. A cell is transported from an associated file which may be of the type wherein selected cells are pneumatically lifted from an associated file up into one of the two tubes in the pair through a file accessing deflector valve. After the cell has cleared the deflector valve, the deflector valve is shut and air is applied to the other file tube of the pair to propel the cell out through its file I/O tube through the object selector valve to the common file I/O channel. If the cell had been received in the other tube of the pair, the object selector valve and air selector valve would have been reversed such that air would have been applied to cause the cell to move out of the other tube. To return a cell to the file, the above sequence is reversed.

While the invention has been particularly shown and described with reference to a preferred embodiment thereof, it will be understood by those skilled in the art that

various changes in the form and details may be made therein without departing from the spirit and scope of the invention.

What is claimed is:

1. In a system wherein carriers are transported from a file through a selected one of a pair of file deflector valves, a pneumatic valving system for mechanically and pneumatically connecting said file deflector valves to a common file I/O channel, said pneumatic valving system comprising:

first and second file tubes pneumatically connected at one extremity thereof;
said first and second file tubes being operatively connected to one of said file deflector valves;
a pneumatic supply; and
means connected to the other extremity of said first and second file tubes operable to selectively connect said file tubes to said pneumatic supply and said common file I/O channel.

2. The pneumatic valving system of claim 1 wherein, when a carrier is in one of said file tubes and said carrier is to be transported to said common file I/O channel, said means connected to the other extremity of said file tubes is selectively operable to connect the said file tube having a carrier in it to said common file I/O channel and the other of said file tubes to said pneumatic supply.

3. The valving system of claim 1 wherein, when a carrier is to be transported from said common file I/O channel into one of said file tubes, said means connected to the other extremity of said file tubes is operable to connect to said common file I/O channel to said one tube and is further operable to effectively disconnect the pneumatic supply from the other of said file tubes.

4. The pneumatic valving system of claim 1 wherein, when a carrier is to be transported from either of said file tubes to said common file I/O channel, said means

connected to the other extremity of said file tubes includes an object selector valve which is operable in a first position to connect said first file tube to said common file I/O channel and operable in a second position to connect said second file tube to said common file I/O channel and further includes an air selector valve operable in a first position to connect said second file tube to said pneumatic supply and operable in a second position to connect said first file tube to said pneumatic supply.

5. The valving system of claim 1 wherein when a carrier is to be transported from said common file I/O channel to one of said file tubes, said means connected to the other extremity of said file tubes includes an object selector valve which is operable in a first position to connect said first file tube with said common file I/O channel and operable in a second position to connect said second file tube with said common file I/O channel and further includes means for effectively disconnecting said pneumatic supply from said first and second file tubes.

6. The valving system of claim 4 wherein said object selector and air selector valves are ganged such that when said object selector valve is in its first position, said air selector valve is in its first position and when said object selector valve is in its second position, said air selector valve is in its second position.
